UNITED STATES PATENT OFFICE.

CONSTANTIN CHILOWSKY, OF PARIS, FRANCE.

PROJECTILE.

1,376,316.

Specification of Letters Patent. Patented Apr. 26, 1921.

Application filed October 24, 1918. Serial No. 259,556.

To all whom it may concern:

Be it known that I, CONSTANTIN CHILOWSKY, a citizen of Russia, residing at Paris, France, have invented certain new and useful Improvements in Projectiles, of which the following is a specification:

The flight of projectiles is greatly influenced by the resistance of the air, and the means hitherto adopted to increase the flight 10 have been based on a study of the shapes of the projectiles, or have consisted in providing high initial velocity.

The applicant, for arriving at the same end, takes into consideration the fact that 15 the resistance to flight depends as much upon the properties of the air as on those of the projectile and increases the range by dealing with the medium traversed, for example by changing its temperature, its density 20 and its composition.

The present invention has for its object a system of reducing the resistance to the flight of a projectile by heating the air through which it passes. To apply the system appropriate means, of which several 25 different forms will be hereinafter described, are arranged on the front portion of the projectile, which means have for their object the heating of the air by discharging into 30 the atmosphere for a considerable distance in front of the projectile, combustible substances which are discharged from a receptacle specially provided for the purpose in the projectile. These substances are such 35 that they burn as fast as they meet with the oxygen in the current of air created by the relative movement of the projectile, the current becomes heated and with it are mixed the residues of the combustion, or combustion 40 is effected in the said receptacle and residues only are discharged into the atmosphere at very high temperature.

In the second case the substances act on the air only through their calorific capacity. 45 In the first case, which is preferably adopted, the substances act both through their calorific capacity as well as through their heat due to combination with oxygen which makes their calorific value greater for a 50 given thermic mass, carried by the projectile.

The combustible should be brought to a state such that its combustion can be produced in a current of air of high velocity and maintained in a continuous and regular 55 manner. If the combustible naturally has pyrophoric properties, it will suffice to pro-

ject it in a pulverized form. In any other case, it is necessary before projecting it into the atmosphere to bring it to an appropriate state of liquid, vapor or gas at a suitably 60 high temperature, by the application of heat. Moreover, in order that the combustion may be sufficiently perfect the combustible should be mixed rapidly and intimately with the air current. This is attained by an 65 atomizer or diffuser which emits the combustible in the form of small jets or thin sheets, or which projects it in small drops.

Among combustible substances, those having pyrophoric properties, such as red phosphorus, or the solution of white phosphorus in carbon bisulfid or gaseous phosphoreted hydrogen, are suitable. The ways of projecting, heating and vaporizing the combustible substances vary according to the 75 nature of the substance employed. Liquid combustibles can be projected and atomized by the action of a gaseous pressure. Solid combustibles can be brought to a gaseous, 80 vaporous or liquid state by partial combustion in the interior of the receptacle, which can be effected by the addition of a proper quantity of a suitable oxid, such as, for example, one of the metallic oxids, a nitrate or sulfur. Thus, in a mixture of about 60 per 85 cent. of red phosphorus and 40 per cent. of oxid of copper, sufficient disengagement is produced to vaporize the remainder of the phosphorus which accordingly burns at the exit of the diffuser.

Thermal substances liberating vapors of incandescent metal may also be conveniently used. Thus bi-oxid of manganese reduced by powder of magnesium or aluminium liberates manganese vapors.

Mixtures of different metallic oxids (for example zinc or lead) with magnesium or aluminium powder produce on reduction incandescent metallic vapors and also vapors of magnesium and aluminium, if these latter substances are in excess.

Incandescent metallic vapors have particular advantages, owing to their spontaneousness of combustion in air. These thermal substances can also be utilized for vaporizing other combustibles, solid or liquid, when they are placed in contact with them, either directly or through the intermediary of metallic walls.

Again, substances of imperfect combustion can be advantageously employed as they contain in the heated products of com-

bustion unburnt combustible matter, such as for example celluloid not containing too much camphor.

Finally, good results may be obtained by 5 adding to one of these mixtures or substances pyrophoric combustibles, such as phosphorus.

The accompanying drawings, which are given by way of example, relate to a mode 10 of and to different forms of means for carrying out the invention in practice, the particulars and the application of which will be explained below. Details of construction, however, may be varied according to 15 circumstances so as to suit best the type of projectile, the nature of the combustible employed and manufacture.

Figure 1 is a cross sectional view of one embodiment of the invention with a receptacle forming the nose piece.

Fig. 2 is a cross sectional view of another embodiment showing a receptacle mounted on the nose of the projectile.

Fig. 3 is a cross sectional view of another embodiment showing a receptacle mounted in the body of the projectile.

Fig. 4 is a cross sectional view of another embodiment showing a receptacle and burner mounted in the nose of the projectile.

Fig. 5 is a cross sectional view of another embodiment showing a double chambered receptacle.

Fig. 6 is a cross sectional view of another embodiment showing a receptacle having means for forcing the combustible through the burner.

Fig. 7 is a cross sectional view of the preferred embodiment of the invention showing a receptacle mounted on the nose of the shell and a burner.

Fig. 1 shows a shell provided in front with a receptacle mounted in the place of the usual pointed nose piece. The explosive charge of the shell is contained in the member 2. A pyrotechnic device 4, with which may be associated if necessary the fuse 5 for detonating the charge 3, allows of the ignition, through the orifice 6 of the combustible 7 on the projectile leaving the mouth of the gun. This double fuse may comprise for example two firing pins, the one concussive acting on a primer at the rear of the gun being fired, the other percussive acting, by momentum, on a primer in front. Ignition being thus obtained on leaving the gun the heated products are liberated from the upper layer through the axial diffuser orifice 8 and burn ahead of the shell. The incandescent sheet 9 which forms is bent by the air current around the shell which thus progresses through a medium of diminished resistance. A heat insulating piece 10 separates receptacle 1 from the explosive 3 in order to prevent

any risk of premature ignition of this explosive.

Fig. 2 represents a modified arrangement of mounting the receptacle 1, in which the receptacle is arranged outside of the shell 70 casing and in such a manner that the outlet holes 11 cause an incandescent layer 9 to be formed in front of the point 12 at the pointed end of the shell in order that the heating of the air may be more perfect for 75 the passage of the shell. In this case, the device for igniting the combustible in the receptacle is situated in front at 4, while that which causes the explosion of the charge is behind at 5.

In the arrangement shown in Fig. 3, the receptacle 1 is housed in the chamber containing the explosive 3 to which it is screwed in a manner similar to that of an ordinary fuse. It has an outside extension 85 comprising a tubulure 13 which carries the ignition device 4 and an ignition retarding appliance 14 which may be constituted by a column of powder adapted to slowly light the combustible 7 at a certain distance 90 from the gun. In the example, the combustible 7, which can be a solid substance such as red phosphorus, is vaporized by means of a thermal core 15, such as aluminium powder with oxid of iron, which disengages from the vapor incandescent phosphorus. The heat insulator 10 is placed inside the receptacle 1. The discharge exit for the incandescent layer 9 is constituted by an annular slot 16 communicating by 100 means of ducts 18, which debouch into a chamber 17, with the duct 13.

In the modification in Fig. 4, the receptacle 1 contains a series of charges 7^a, 7^b, 7^c, 7^d, each of a different nature, adapted to 105 produce variations in the progress of the combustion. The exit is represented as being made through an axial twyer 8, having a ring of holes 11. In Fig. 5 an arrangement of the same kind, as in Fig. 4, is 110 formed with two receptacles 1^a and 1^b containing respectively the combustible charges 7^a and 7^b. Between these two charges, a pyrotechnic device 19 is arranged in such a manner that the ignition of 7^b is only effected at a predetermined time after the end of the combustion of the charge 7^a. The incandescent layer 9 may be thus produced only at the beginning and end of the flight of the projectile and may be suppressed 115 during the intermediate period of the passage of the projectile in regions of high altitude, where the air is of low density. Such arrangement gives rise to material economy in the use of combustible in long 120 flight projectiles. The heat insulator 10 is here shown outside the part 1^b.

The arrangement shown in Fig. 6 is more particularly suited for the case where a pyrophoric liquid combustible is employed,

such as the solution of white phosphorus in carbon bi-sulfid. The liquid placed in 21 would be ejected through the orifices 8 and 11 of the diffuser, under the action of a gas 5 pressure produced in the primer 20. To this end, the concussion at the firing of the gun sets up in primer 20, either the liberation of compressed or liquified gas or a chemical reaction between the substances 10 yielding as residues high pressure gases. The liquid jets passing through holes 11 are atomized into a sheet of drops by collision with the opposing solid walls. In order to prevent leakage of the liquid before the 15 shell is brought into use, a heavy stopper 22 is placed over the duct feeding the several orifices. Its inertia at the firing of the gun, will automatically remove it and cause a passageway to be left.

20 In the case where the liquid combustible employed is not pyrophoric, it is of course necessary to bring it to a state of division and to a temperature sufficiently high to ignite it. A petrol burner with heated walls 25 may be provided for preliminarily heating it. Lastly, the orifices may be projected in such a way that the flames cannot be extinguished.

The stopper for the orifices for the liquid 30 can be constituted by a highly combustible body or be self-destructive in any suitable manner at the firing of the gun.

Fig. 7 relates to an application of the invention to a tracer shell. The shell represented is a tracing and incendiary one; it is 35 filled with a combustible mixture of phosphorus and oxid of copper. The concussion fuse 4 is placed in the upper part at the base of the tube 22 which is connected and terminates with the outlet orifices at an appropriate 40 distance in front of the shell nose. This provision of empty tubes at the front part of the projectiles can also be applied to the other arrangements described. It is 45 convenient, in each particular application, to determine the best form to adopt to produce the maximum efficiency. The ejection of the combustible should occur generally at a distance from the shell appropriately 50 determined for heating the air sufficiently in front of the projectile. The best distance varies according to the velocity of the projectile, its form, its caliber and also on the combustible employed.

55 It will be advantageous, in certain cases to burn the combustible during the initial part of the trajectory when the projectile has great velocity and experiences great resistance on the part of the air traversed.

60 It is quite evident, moreover, that the

above arrangements are not in any way limited, and the parts of the devices employed can, according to circumstances, be given any proportions, without departing from the domain of the invention.

Having thus described the nature of the said invention and the best means I know of carrying the same into practical effect, I claim:—

1. A method of reducing the resistance to 70 the flight of a projectile, which consists in heating the air around the nose of the projectile during its flight.

2. A projectile having means for heating the air in advance thereof. 75

3. A projectile having means for heating the air in advance thereof, said heating means comprising a fuel reservoir and a burner in the front of the projectile.

4. A projectile having means for heating 80 the air in advance thereof, said heating means comprising a fuel reservoir and a burner in the front of the projectile, said burner projecting from the front of the axis of the projectile. 85

5. A projectile having means for heating the air in advance thereof, said heating means comprising a fuel reservoir and a burner in the front of the projectile, said burner being pointed. 90

6. A projectile having means for heating the air in advance thereof, said projectile having a hollow interior.

7. A projectile having means for heating 95 the air in advance thereof, said projectile having a hollow interior, and a fuel reservoir in said hollow interior.

8. A projectile having means for reducing the resistance to its flight by heating the air around the nose of the projectile, comprising a receptacle for combustible connected to the front of the projectile, means for igniting the combustible and means for directing the burning gases of combustion 100 around the nose of the projectile. 105

9. A projectile according to claim 8, said igniting means comprising a pyrotechnic device having an orifice.

10. A projectile according to claim 8, said means for directing the gases comprising a 110 chambered nose portion having a longitudinal bore.

11. A projectile according to claim 8, said means for directing the gases comprising a 115 tubular extension having communicating transverse bores near its outer end.

In witness whereof I have hereunto signed my name.

CONSTANTIN CHILOWSKY.
